Primary Examiner — Karen E Kearney*Assistant Examiner* — Adam C Mager(74) *Attorney, Agent, or Firm* — Mark D. Bowen; Malin Haley DiMaggio & Bowen, P.A.(57) **CLAIM**

The ornamental design for a sea chest for marine vessels, as shown and described.

DESCRIPTION

FIG. 1 is a top front perspective view of a sea chest for marine vessels in accordance with the present invention;

FIG. 2 is a bottom rear perspective view thereof;

FIG. 3 is a top view thereof;

FIG. 4 is a bottom view thereof;

FIG. 5 is a left side view thereof, with the right side view being a mirror image;

FIG. 6 is a front view thereof; and,

FIG. 7 is a rear view thereof.

The broken lines in FIGS. 1-3 and 5-7 form no part of the claimed design.
